SAFETY APPARATUS FOR MINE VEHICLES

James T. Tackett, Grass Valley, Calif.

Application August 26, 1941, Serial No. 408,401

1 Claim. (Cl. 188—168)

This invention appertains to new and useful improvements in safety means for mine cars and elevators.

The principal object of the present invention is to provide automatic brake means for mine cars which will operate upon a break occurring in the operating cable thereof.

Other objects and advantages of the invention will become apparent to the reader of the following description.

In the drawings:

Figure 1 represents a fragmentary top plan view showing a mine car and the present invention in broken lines installed thereon.

Figure 2 is a longitudinal sectional view through a mine tunnel or shaft showing in side elevation a mine car equipped with the present invention.

Figure 3 is a bottom plan view of the brake mechanism.

Figure 4 is a front end elevational view.

Referring to the drawings wherein like numerals designate like parts, it can be seen in Fig. 2, that numeral 5 denotes a mine shaft or tunnel having a mine trackway 6 therein. This trackway includes ties 7 and between the rails of the trackway are closely spaced rails 8, 8 for use in conjunction with the present invention.

Numerals 9 denotes a mine car having wheels 10 riding the trackway 6 and numeral 11 generally refers to the present invention which is co-operative with the auxiliary rails 8, 8.

In carrying out the present invention, it can be seen that numeral 12 denotes a plate having upwardly disposed and flanged end walls 13 secured to the bottom side of the car 9.

Secured in a position extending transversely across the plate 12 is a bar 14. The intermediate portion of this bar 14 is offset downwardly as at 15 to afford clearance for upper and lower links 16 and 17. The outer end portions of the bar 14 are suitably spaced from the plate 12 by suitable spacing means and interposed between these spaced end portions of the bar are bellcrank-shaped levers 18, the heel portions of which are pivotally secured in place by bolts 19 passing through the plate 12, heel portions of the levers 18 and the bar 14. One end of each of these levers 18 has a collar-like structure 20 while the other or diverged end portion is serrated as at 21 for biting engagement with the corresponding auxiliary rail 8.

Lugs 22 depend from the side edges of the plate 12 and short flanges 23, 23 are struck from the plate 12 and depend as suggested in Figure 3. Interposed between each lug 22 and its opposed flange 23 is a guide rod 24 which also extends through the collar-like structure 20 of the corresponding lever 18.

On each of the rods 24 and interposed between 60

the corresponding collar-like structure 20 and the adjacent lug 22 is a coiled compression spring 25. These springs have a tendency to rock the levers 18 in a direction with the serrated edges 21 of the levers against the auxiliary rails 8, 8.

As shown in Figure 3, the upper and lower links 16 and 17 have their inner ends bolted together, by a bolt 26 extending downwardly through openings in the adjacent ends of the said links. Numeral 27 denotes a hauling cable which extends to connect to a slide rod 35, this rod extending through a lug 36 and being connected to the bolt 26. A coiled compression spring 37 is located on this slide rod and interposed between the said bolt are the links 16, 16 and the lug 36, so that in the event the cable 27 breaks the spring 37 will function along with the springs 25, 25 to cause operation of the levers 18. In other words, this spring 37 is an added precaution that the levers 18, 18 will operate even though the springs 25, 25 become defective.

A bar 28 is disposed across the top of the plate 12 and has depending end legs 29, 29 which overlap the auxiliary rails 8, 8 and prevent spreading 25 of the said rails when the brake mechanism is operated.

It can now be seen that in the event the cable 27 breaks, the springs 25 will act to rock the levers 18 and cause the serrated ends 21 to bite against the auxiliary rails 8, 8, thus stopping the car 9.

While the foregoing specification sets forth the invention in specific terms, it is to be understood that numerous changes in the shape, size and materials may be resorted to without departing from the spirit and scope of the invention as claimed hereinafter.

Having described the invention, what is claimed 40 as new is:

In combination, a wheeled vehicle, a trackway, brake means on the vehicle, a draft cable for the vehicle, said cable being directly connected to the brake mechanism and adapted to release said brake mechanism when under tension and to apply said brake when released, said brake mechanism comprising a pair of rockable levers having track engaging ends, spring means engaging the opposite ends of the levers for forcing the first-mentioned ends into frictional contact with the rails, toggle links connected with the levers, means connecting the cable to the toggle, spring means urging the links in a direction to apply the brake, said cable when in hauling tension moving the links in the opposite direction for releasing said brake, and means for engaging upon the opposite sides of the rails to prevent spreading of the rails upon application of the brake.

JAMES T. TACKETT.
